(57) **CLAIM**

The ornamental design for a desk, as shown and described.

DESCRIPTION

FIG. 1 is a front-right perspective of an embodiment of the desk according to the claimed design shown in a lowered position;

FIG. 2 is a front view of the desk of FIG. 1;

FIG. 3 is a rear view of the desk of FIG. 1;

FIG. 4 is a left side view of the desk of FIG. 1;

FIG. 5 is a right side view of the desk of FIG. 1;

FIG. 6 is a top view of the desk of FIG. 1; and,

FIG. 7 is a front-right perspective of the desk of FIG. 1 shown in a raised position.

The features shown in broken lines represent portions of the desk which form no part of the claimed design.

1 Claim, 7 Drawing Sheets
